CLAIM

The ornamental design for a luminous drawing surface and night light, as shown and described.

DESCRIPTION

FIG. 1 is a front perspective view of a luminous drawing surface and night light showing my new design;
FIG. 2 is a rear perspective view thereof in a closed position;
FIG. 3 is a front elevational view of FIG. 1 with the top view being a mirror image thereof;
FIG. 4 is a rear elevational view with the bottom view being a mirror image thereof; and,
FIG. 5 is a left side elevational view with the right side being a mirror image thereof.
